Attorneys

Patented Aug. 4, 1925.

UNITED STATES PATENT OFFICE.

CHARLES A. MOORE, OF ST. PAUL, MINNESOTA.

REFRIGERATOR.

Application filed August 15, 1924. Serial No. 732,342.

To all whom it may concern:

Be it known that I, CHARLES A. MOORE, a citizen of the United States, residing in St. Paul, in the county of Ramsey and State of Minnesota, have invented a new and useful Refrigerator, of which the following is a specification.

My invention relates to improvements in refrigerators for domestic and other uses.

10 Recent developments in small refrigerating machines for ice boxes are accompanied with the demand for a simple, durable, inexpensive and efficient storage structure for the preservation of commodities under refrigeration afforded by such machines.

One object of the present invention is to supply a refrigerator embodying the above named features, a further object being to provide for an arrangement of parts in such 20 a device, wherein the storage space is relatively large and whereby ready access may be had to the stored articles.

With the foregoing and other objects in view, which will appear in the following 25 description, the invention resides in the novel combination and arrangement of parts and in the details of construction herein-after described and claimed.

In the drawings, Fig. 1 is a vertical, central, sectional view of a refrigerator embodying my invention; Fig. 2 is an elevational view thereof; Fig. 3 is a transverse sectional view taken on the line 3—3 of Fig. 1 and Fig. 4 is an enlarged sectional view in 35 detail, the same being taken on the line 4—4 of Fig. 3.

Referring to the drawings, it will be seen that my improved refrigerator includes a box structure A having a bottom 10, cylindrical sidewall 11 and cover 12. Said parts of said box structure are constructed of any suitable heat insulating materials, the sidewall 11 being formed with doorways 13 fitted with doors 14, and the cover 12 being removably fastened on the sidewall 11 as by means of screws 15 reaching through said cover and threaded into the upper edge of said sidewall. A core structure B depending from the cover 12 and hanging axially of the chamber b within the box structure A includes concentric air ducts 16, 17 and a pipe 18 coiled turn upon turn about the outer duct 16. Said outer duct 16 is a pipe, the upper end of which is fitted

and fastened in a central opening in the cover 12. Stopping short of the floor of the chamber b, said duct 16 provides communication between the outside atmosphere at the top of the box structure A and the chamber b at the lower portion thereof. The duct 17 is a pipe arranged within the duct 16, the upper end of said pipe being fitted with radial branches 17^a reaching through the wall of the duct 16 and affording communication between the upper end of the duct 17 and the upper portion of the chamber b. The lower end of said pipe or duct 17 hangs beneath the lower end of the duct 16, said depending end of said duct 17 being received in a well 19 formed in the bottom 10 to receive water of condensation forming within the chamber b and drained to the center of the floor thereof. A drain pipe 20 leading from the lower portion of the chamber b through the bottom 10 is arranged with the upper end thereof reaching upward into the well 19 and into the lower end of the duct 17. The upper edge of said drain pipe 20 is depressed within the well 19 and is considerably smaller in outside diameter than the inside diameter of the duct 17. With the duct 17 fitting over the drain pipe 20, as above described, it will be understood that water in the well 19, though free to drain into the pipe 20, seals the joint between said duct 17 and pipe 20. Thus arranged, the water drain pipe 20 serves additionally as a continuation of the air duct 17. The pipe 18 is coiled closely about the outer duct 16, a feed branch 18^a leading downward between the ducts 16, 17 to the lower turn of the pipe and a return branch 18^b leading upward between said ducts from the upper turn of said pipe. These pipe branches 18^a, 18^b connect with any suitable refrigerating machine (not shown) mounted on the box structure A, or elsewhere, as may be desired.

I provide a shelf for each doorway 13, each shelf being adapted to revolve like a turn-table to present articles thereon in position readily accessible through its respective doorway. A circular piece of woven wire open at the center thereof to receive the core structure B constitutes a shelf 21. A binder ring 22, reinforcing the wire shelf 21 at the margin thereof, supplies a carriage frame to the underside of which are secured

a number of socket members 23, each embracing a ball-traveler 24 therein. These ball-travelers 24 ride upon rails 25 of a track 26, said track being circular in form 5 and secured to the inner side of the sidewall 11.

In use, the shelves 21 are turned to bring the produce thereon into position accessible through the doorways 13. Conducted 10 through the pipe 18, a refrigerant therein reduces the temperature of the air within the provision chamber *b* and also within ducts 16, 17, the arrangement of the feed branch 18^a within the duct 16 aiding in the 15 reduction of temperatures therein and making for structural compactness. Cooled in the ingress duct 16 and egress duct 17 air settles in the duct 16 from the outer atmosphere to the lower portion of the chamber *b* 20 and in the duct 17 from the upper portion of said chamber to the outer atmosphere. Being pre-cooled in its travel through the ingress duct 16 and past the feed branch 18^a the air flowing into the chamber *b* is readily 25 further reduced in temperature by the refrigerant in the turns of the pipe 18 within said chamber.

Arranging the egress duct 17 within the ingress duct 16 and the coils of the pipe 18 outside of said ingress duct 16, provides for the economical use of the refrigerant in effecting the exhaustion of air from the chamber *b*. The combination of the water drain pipe 20 with the air duct 17, whereby 35 the former provides a continuation of the latter for the egress of air from the chamber *b* is an advantageous feature of the invention.

Changes in the specific form of my invention, as herein disclosed, may be made 40 within the scope of what is claimed without departing from the spirit of my invention.

Having described my invention, what I claim as new and desire to protect by Letters Patent is:

1. In a refrigerator, a box forming a provision chamber and comprising a floor, a cylindrical sidewall and a cover, the sidewall having a doorway therein and a closure 50 for said doorway, a core structure in said box comprising a duct arranged axially of said chamber, said duct communicating with the outer air at its upper end and opening into the lower portion of the box at its lower end, a pipe for a refrigerant closely coiled about said duct, the floor of said box having an axial well therein to catch water of condensation, a drain pipe in the bottom 55 of the box, the upper end thereof reaching upward within the well axially thereof, a second duct arranged within and axially of said first duct, said second duct communicating at its upper end with the upper portion of the chamber, the lower end of said duct loosely encircling said upper end of

said drain pipe, and a ring-like shelf enclosing said core structure and mounted within said box to turn about said structure.

2. In a refrigerator, a box forming a provision chamber, a duct in said chamber communicating with the outer air at its upper end and opening into the lower portion of the box at its lower end, the bottom of said box having a well therein to catch water of condensation, a drain pipe in the bottom of the box, the upper end thereof reaching upward in the well, a second duct communicating at its upper end with the upper portion of the chamber, the lower end of said duct loosely encircling said upper end of said drain pipe, and a pipe for a refrigerant associated with said ducts. 70 75 80

3. In a refrigerator, a structure forming a provision chamber, two upright ducts in said chamber, one duct providing communication between the outside atmosphere at the upper portion of the structure and the interior of the chamber at the bottom thereof, the other duct providing communication between the interior of the chamber 90 at the upper portion thereof and the outside atmosphere at the lower portion of said structure, a pipe for a refrigerant associated with said ducts, and a ring-like shelf mounted within said chamber and adapted 95 to turn about said ducts and pipe. 100

4. In a refrigerator, a structure forming a provision chamber, two concentric ducts arranged axially within said chamber, the outer duct providing communication between the outside atmosphere at the upper portion of the structure and the interior of the chamber at the bottom thereof, the inner duct providing communication between the interior of the chamber at the upper portion thereof and the outside atmosphere at the lower portion of said structure, and a pipe for a refrigerant coiled turn upon turn about said outer duct, said pipe having a feed branch leading downward between said 110 ducts to the lowermost turn of said pipe. 105 110

5. In a refrigerator, a structure forming a provision chamber, two upright ducts in said chamber, one within the other, the outer duct providing communication between the outside atmosphere at the upper portion of the structure and the interior of the chamber at the bottom thereof, the inner duct providing communication between the interior of the chamber at the upper portion 115 thereof and the outside atmosphere at the lower portion of said structure, and a pipe for a refrigerant coiled about said outer duct. 120

6. In a refrigerator, a box structure forming a provision chamber, a core structure depending from the cover of the box structure and including two concentric ducts and a refrigerating pipe coiled about the outer duct, said outer duct providing com- 125 130

munication between the outside atmosphere at the upper portion of the structure and the interior of the chamber at the bottom thereof, the inner duct providing communication between the interior of the chamber at the upper portion thereof and the outside atmosphere at the lower portion of said

structure, and a provision shelf within the box structure, said shelf encircling said core structure and revoluble about the same. ¹⁰

In testimony whereof, I have signed my name to this specification.

CHARLES A. MOORE.
